UNITED STATES PATENT OFFICE.

GEORGE W. WALKER, OF MALDEN, MASSACHUSETTS.

GRATE-BAR.

SPECIFICATION forming part of Reissued Letters Patent No. 10,296, dated March 13, 1883.

Original No. 246,645, dated September 6, 1881. Application for reissue filed February 2, 1883.

To all whom it may concern:

Be it known that I, GEORGE W. WALKER, of Malden, county of Middlesex, and State of Massachusetts, have invented a new and useful Improvement in Grate-Bars, of which the following description, in connection with the accompanying drawings, is a specification.

This invention relates to grate-bars, and is shown embodied in a dumping-grate.

10 The object of my invention is the production of a grate all the bars of which may be vibrated independently by cams, the said grate-bars being pivoted upon a rod supported in the dumping-frame at or near its center. Each 15 grate-bar at its outer or movable end is guided by suitable combs or teeth forming part of the dumping-frame. The shaft which carries the cams for operating the grate-bars serves also as a supporting and trunnion shaft for the 20 dumping-frame, thus making my improved grate-bar applicable to any furnace, in place of the usual grate-bar of substantially the same shape. Each of my improved grate-bars is ex- 25 tended only a part of the way across the dumping-frame, and is pivoted at its inner end, so that when a downward projection of the grate-bar is acted upon by a cam the outer end of the grate-bar will be raised and lowered rapidly. Adjacent grate-bars are provided with projec- 30 tions and shoulders to prevent the grate-bars leaving the notches or combs of the dumping-frame when the latter is turned over.

Figure 1 represents in top view a grate and dumping-frame embodying my invention; Fig. 35 2, a section on the dotted line $x-x$, Fig. 1. Fig. 3 is a partial side elevation of the dumping-frame. Fig. 4 is a front end elevation of the dumping-frame, and Fig. 5 is a side elevation of the cam-shaft.

40 In the drawings, A represents the dumping-frame, it being oblong, the sides a' of the frame being provided with a series of upright combs or fingers, 3, in the notches between which the series of grate-bars b c , near their ends, are 45 entered and guided. The grate-bars are each provided with a suitable hole to fit a rod, d , the end of which has suitable bearings in the end a of the dumping-frame, and at one end is covered by a cap, a^3 , secured to the front 50 end of the dumping-frame, the projections 45 (see Fig. 1) extending over the said rod d near

its ends. The grate-bar b has a downwardly-projecting finger or arm, b' , and the shoulder b^2 , and each grate-bar c has a corresponding downwardly-projecting arm or finger, c' , and the reversely-placed notch or shoulder c^2 , these arms b' and c' , below the pivotal point d of the grate-bars, being suitably shaped to present proper cam-surfaces to be acted upon by short cam projections e , more or less in number, and arranged, as shown in Fig. 5, on the shaft e^2 , the front end of which is squared, as at e^3 , to receive the usual wrench or handle with which to rotate the said shaft e^2 , to vibrate the grate-bars, and also to turn over the dumping-frame. 55 As the shaft e^2 is rotated in the direction of the arrow, &c., Fig. 2, the cam projections will strike against the portions 6 of the grate-bars c and the portions 7 of the grate-bars b , and will move them so as to elevate the outer ends 60 of the grate-bars, and as the cams pass the shoulders b^2 c^2 the grate-bars, by their own gravity and the weight of the fuel upon them, 65 will drop.

The left-hand end of the shaft e^2 serves as 70 the journal for the dumping-frame, and the neck 8 of the right-hand end of the said shaft, (see Fig. 1,) which in practice will be from two to three inches in length, serves as a journal to fit a proper bearing to sustain the front part 80 of the dumping-frame. When it is desired to tip over the dumping-frame, the shaft e^2 will be turned in the direction opposite the arrow, Fig. 2, when the cam projections e will strike squarely against the shoulders c^2 and b^2 , and 85 will turn the dumping-frame over toward the left, as herein shown, the frame being capable of being turned over only in that direction. As described, it will be understood that this shaft e^2 serves the purpose of the journal for 90 the dumping-frame, and is provided with cams by which to vibrate the grate-bars when the shaft is turned in one direction, and the grate-bars are so shaped that when the said shaft is turned in the opposite direction the cams 95 thereon, operating against the shoulders of the grate-bars, will turn the dumping-frame over.

Each grate-bar b has a projection, m , to strike against a shoulder, 10, of the grate-bar c in line with it, and each grate-bar c has a similar projection, n , to engage a shoulder, 12, of the grate-bar b in line with it, so that when the

dumping-frame is turned over the said projections meet the said shoulders and prevent the grate-bars turning so far upon the rod *c* as to permit the ends of the grate-bars to leave the notches between the fingers or projections 3 of the dumping-frame A.

The cap *a*³, at the front end of the dumping-frame, serves as a cover to retain the shaft *e*² in its bearing in the dumping-frame. This cap *a*³, as shown in Fig. 4, is hooked at one end to engage a lug, *f*, of the dumping-frame, and at its other end the cap has a leg to enter a socket of the dumping-frame, the leg being secured in the said socket by means of a pin, *o*, extended therethrough, as shown in the said figure.

These grate-bars, fixed at their inner ends substantially at or near the longitudinal center of the dumping-frame, are vibrated up and down at their outer ends, moving only at the 20 said outer ends.

I do not broadly claim a grate-bar mounted loosely in a dumping-frame, so that each end of the grate-bar may be moved up and down by means of cams on an independent shaft other than that which serves as the journals 25 for the dumping-frame.

I claim—

1. The combination, with the frame, of grate-bars *b c*, pivoted at their inner ends, and a cam-shaft to operate upon downwardly-extended 30 portions of and vibrate the said grate-bars about their pivotal point, substantially as described.

2. The pivoted grate-bar provided with a 35 downwardly-projecting arm, shouldered as described, combined with a dumping-frame and with a cam-shaft which, turned in one direction, will vibrate the said grate-bar, and in the other direction will turn over the dumping-frame, substantially as described.

3. The dumping-frame provided with the fingers or projections 3 to receive the grate-bars, combined with the independent grate-bars *b c*,

having their inner ends pivoted substantially at the center of the dumping-frame, as set forth. 45

4. The frame, its rod *d*, and the series of grate-bars *b c*, the bars *b* being substantially in line with the series of grate-bars *c*, one grate-bar *b* being at one side of the frame, while a grate-bar *c* is at the opposite side of the frame, in 50 line with it, substantially as described.

5. The dumping-frame, its cam-shaft, and rod *d*, combined with the series of grate-bars *b c*, provided with projections *m n* and shoulders 12 10, to operate substantially as described. 55

6. The dumping-frame and a series of grate-bars mounted thereon, combined with a shaft adapted to serve as the journal for the dumping-frame, and provided with cams to operate the grate-bars, substantially as described. 60

7. A dumping-frame having a series of independently-movable grate-bars mounted thereon, combined with a cam-shaft which both actuates the grate-bars and serves as the journal for the dumping-frame, the same shaft 65 when rotated in one direction operating only the grate-bars on the dumping-frame, and in the other direction turning the dumping-frame.

8. The dumping-frame combined with the cam-shaft to actuate the grate-bars, the said 70 shaft being arranged to serve as the journals about which the said frame may be turned when it is desired to dump the same.

9. The dumping-frame and the cam-shaft to support it, combined with a series of movable 75 grate-bars having curved surfaces, against which the cams act in one direction of the shaft to move the grate-bars, and with shoulders against which the cams of the cam-shaft act when the latter is rotated in an opposite direction to dump the dumping-frame, substantially 80 as described.
